UNITED STATES PATENT OFFICE

ALBERT SIDNEY RAWORTH, OF BEARSDEN, SCOTLAND

DESIGN FOR AN UNDERFRAME FOR A TREADLE SEWING MACHINE

Application filed April 30, 1932, Serial No. 43,663, and in Great Britain March 31, 1932. Term of patent 14 years.

To all whom it may concern:

Be it known that I, ALBERT SIDNEY RAWORTH, a subject of the King of Great Britain, residing at Elbana, Thorn Drive, Bearsden, Dumbartonshire, Scotland, have invented a new, original, and ornamental Design for an Underframe for a Treadle Sewing Machine, of which the following is a specification, reference being had to the accompanying drawing, forming part thereof.

Figs. 1 and 2 are, respectively, front and rear perspective views of an underframe for a treadle sewing machine, showing my new design.

I claim:

The ornamental design for an underframe for a treadle sewing machine, as shown.

A. S. RAWORTH.
